United States Patent Office

Des. 214,681
Patented July 15, 1969

214,681

FOOT MAT

Ronald E. King, 12 Irene Crescent, Kingsgrove,
New South Wales 2208, Australia

Filed Nov. 21, 1968, Ser. No. 14,576

Term of patent 14 years

Int. Cl. D6—05; D7—06

U.S. Cl. D44—31

Fig. 1.

Fig. 2.

FIG. 1 is a plan view of a foot mat showing my new design; and

FIG. 2 is an enlarged scale fragmentary plan view of the upper left corner thereof.

I claim:

The ornamental design for a foot mat, substantially as shown.
